(57) **CLAIM**

The ornamental design for a pole (for supporting plants), as shown and described.

DESCRIPTION

FIG. 1 is a perspective view of a pole (for supporting plants);
FIG. 2 is a front view thereof;
FIG. 3 is a rear view thereof;
FIG. 4 is a right-side view thereof;
FIG. 5 is a left-side view thereof; and,
FIG. 6 is a top view thereof.

The broken lines depict unclaimed portions of the pole (for supporting plants) and form no part of the claimed design. The dot-dash chain lines depict a boundary of the claimed subject matter and form no part of the claimed design.
